BACTERIOLOGICAL DISH RACK

Ronald W. Emmitt, Farmington, Mich., assignor to
Emmitt Scientific, Inc., Farmington, Mich.

Filed Nov. 24, 1969, Ser. No. 20,265

Term of patent 14 years

Int. Cl. D24—02

U.S. CL. D16—1

FIG. 1

FIG. 2

FIG. 3

FIG. 4

FIG.5

FIG. 6

FIG. 7

FIG. 8

FIG. 1 is a perspective of a bacteriological dish rack, showing my new design;

FIG. 2 is a top plan view thereof;

FIG. 3 is an end elevation view thereof;

FIG. 4 is a front elevation view thereof;

FIG. 5 is a perspective view of a modified embodiment of the bacteriological dish rack illustrated in FIG. 1;

FIG. 6 is a top plan view thereof;

FIG. 7 is an elevation end view thereof; and

FIG. 8 is a front elevation view thereof.

I claim:

The ornamental design for a bacteriological dish rack, as shown and described.
